E. E. ALLEN.
VULCANIZING PRESS.
APPLICATION FILED AUG. 11, 1920.

1,415,082.

Patented May 9, 1922.

UNITED STATES PATENT OFFICE.

EDWARD E. ALLEN, OF ERIE, PENNSYLVANIA, ASSIGNOR TO ALLEN MACHINE COMPANY, OF ERIE, PENNSYLVANIA, A CORPORATION OF PENNSYLVANIA.

VULCANIZING PRESS.

1,415,082.

Specification of Letters Patent. Patented May 9, 1922.

Application filed August 11, 1920. Serial No. 402,879.

To all whom it may concern:

Be it known that I, EDWARD E. ALLEN, a citizen of the United States, residing at Erie, in the county of Erie and State of Pennsylvania, have invented new and useful Improvements in a Vulcanizing Press, of which the following is a specification.

This invention is particularly designed for use with vulcanizing presses which have a vulcanizing chamber of considerable length which is provided with a ram adapted to traverse the chamber so that a large number of tires may be vulcanized in one operation. The ram in such a vulcanizing chamber is usually actuated by a hydraulic lift, the piston extending from the hydraulic cylinder into the vulcanizer. The mounting of the vulcanizing chamber is one of some difficulty because of the strain to which it is subjected and the necessity for alining the chamber with the piston. The present invention is directed to the connection between the vulcanizing chamber and the hydraulic cylinder by means of which the mounting for the chamber is improved.

The invention is illustrated in the accompanying drawings wherein

Fig. 1 shows a vertical central section of the device.

Fig. 2 a plan view of the base.

Fig. 3 a bottom view of the head of the vulcanizing chamber.

1 marks the head of the vulcanizing chamber, and 2 the shell of the vulcanizing chamber. This shell is commonly formed of steel and riveted to the head 1. A ram 3 operates in the vulcanizing chamber and is actuated by a piston 4 with sufficient travel to carry the ram to the top of the chamber. The piston 4 extends from the plunger 5. The plunger 5 operates in a hydraulic cylinder 6. The base 7 is carried ordinarily by a concrete bed 8 having a pit or well 9 into which the cylinder 6 extends, the cylinder being hung or suspended from the base 7.

The piston extends through the usual glands 10 and 11 on the head and base respectively, these glands making a steam-tight and water-tight joint respectively.

50 The base has the ribs 12 extending to post supports 13. The post supports have perforations extending through them and the posts 14 extend through these perforations, the posts having shoulders 15 resting on the supports 13. Nuts 16 are screwed on to the

lower ends of the posts so as to securely clamp them in place. The head 1 is spaced from the base 7. The head 1 has the ears 17 extending from it, these ears being provided with perforations 18 through which the posts extend. The posts are screw-threaded and provided with the nuts 19 which form adjustable shoulders on which the head rests. By adjusting the nuts 19 the shell 2 can be alined with the piston so that the ram will travel with equal clearance throughout the length of the shell. This is of importance because the shell is ordinarily made of steel and riveted to the head 1 and it is, therefore, very difficult to get the shell 70 in exact alinement with the head even though the head may be turned accurately. By means of the adjusting nuts 19 any inaccuracy may be corrected. The nuts are locked in adjustment by the jam nuts 20 75 and the head is clamped on the shoulder 19 by the nuts 21. Ribs 22 are arranged on the head preferably extending to the ears 17. While I have shown 4 posts it will be understood that the invention is not limited 80 to the use of this number.

What I claim as new is:—

1. In a vulcanizing press, the combination of a vulcanizing chamber having a bottom head; a hydraulic chamber in alinement with the vulcanizing chamber; a base on which the hydraulic chamber and vulcanizing chamber are mounted; a ram in the vulcanizing chamber; a piston extending from the ram through the head and base; and a series 85 of posts each detachably and separately secured to the head and base and supporting the vulcanizing chamber.

2. In a vulcanizing press, the combination of a vulcanizing chamber having a bottom head; a hydraulic chamber in alinement with the vulcanizing chamber; a base on which the hydraulic chamber and vulcanizing chamber are mounted; a ram in the vulcanizing chamber; a piston extending from the ram through the head and base; a series 95 of posts secured to the head and base and supporting the vulcanizing chamber; and means for adjusting the posts to aline the vulcanizing chamber.

3. In a vulcanizing press, the combination of a vulcanizing chamber having a bottom head; a hydraulic chamber in alinement with the vulcanizing chamber; a base on which the hydraulic chamber and vulcaniz- 110

ing chamber are mounted; a ram in the vulcanizing chamber; a piston extending from the ram through the head and base; and a series of posts secured to the head and base, said posts extending into the head and base and each post having an adjustable shoulder at one end supporting the vulcanizing chamber.

4. In a vulcanizing press, the combination of a vulcanizing chamber formed with a head; a shell secured to the head and extending therefrom; a hydraulic cylinder; a

base on which the cylinder is mounted, said base having perforated post supports; shouldered posts resting on the supports; 15 perforated projections on the head through which the posts extend; nuts screwed on to the posts on which the projections rest; and nuts arranged above the projections for clamping the projections on the posts. 20

In testimony whereof I have hereunto set my hand.

EDWARD E. ALLEN.
